UNITED STATES PATENT OFFICE

CHARLES WALCOTT STRATFORD, OF SAN FRANCISCO, CALIFORNIA.

METHOD OF HEATING FLUIDS AND APPARATUS USED THEREFOR

Application filed December 10, 1926. Serial No. 153,903.

This invention relates to improvements in methods of heating fluids and apparatus used therefor as particularly adapted to the heat treatment of hydrocarbon oils, either to raise the oil to a distillation temperature or to a temperature sufficient to bring about cracking of the hydrocarbons heated.

In the distilling branch of petroleum refining, it is usual practice to heat petroleum or its distillates for the purpose of distillation or cracking in shell stills or pipe stills.

These methods entail the use of shell stills, either batch or continuous in operation, positioned over furnace settings, the heat of fuel combustion being transmitted to the oil by radiant heat or heat of convection. Likewise in pipes heat is transmitted from the combustion of fuel to the oil circulated through tubes or pipes.

Recognizing the difficulties and inefficiencies of these methods and equipment I propose a furnace setting in which are vertically positioned cylindrical heating tubes, the combustion gases being circulated around these heating tubes consecutively while the oil is progressively advanced through the tubes in an opposed direction to the passage of the combustion gases. The oil in the cylindrical heating tubes is rotated at a high velocity in order that an efficient heat exchange will be effected between the combustion gases and the liquid oil.

Fig. 1 is a diagrammatic view of an oil heating system, showing the arrangement of the heating cylinders and the manner in which they are connected into the system.

Fig. 2 is an enlarged detail of the furnace setting.

Fig. 3 is a view taken along the line 3—3 in Fig. 2.

Fig. 4 is a sectional view of one of the cylinders in which the liquid is spun at high velocity.

Fig. 5 is a view taken along the line 5—5 in Fig. 4, and

Fig. 6 is a view taken along the line 6—6 in Fig. 4.

Referring to the drawings, at 1 is designated a furnace setting consisting of separate heating chambers, 2, 3, 4 and 5, sepa-

rated by baffle walls 6, 7 and 8. The furnace is preferably heated by oil or gas burners, not shown, the combustion gases, however, being introduced tangentially through the flues 9 into the bottom of the chamber 2, so that they will proceed in a spiral course upwardly through the chamber, this course of the combustion gases being determined by the pitch of the initial velocity of injection and combustion expansion, and if needed, spiral baffles 60 may be placed in the walls of the chamber, to produce spiral circulation of the gases. From the chamber 2 the combustion gases pass by a duct through the baffle wall 6, entering the second chamber 3 tangentially. 65 Therein they are directed in a spiral course downwardly around the heating cylinder positioned in this chamber. The combustion gases pass from the lower part of the chamber 3 and follow a course in the chamber 4, 70 similar to that in the chamber 2. From the top of the combustion chamber 4 the partially cooled combustion gases pass downwardly over a bank of preheating tubes 9 positioned in the chamber 5. The combustion gases are 75 finally discharged through a flue 10, shown in Fig. 1.

The oil to be treated is withdrawn from the storage tank 11 and directed by means of a pump 12 through a heat exchanging device 80 13, where its temperature is raised by heat transfer with a hot oil taken from a later stage in the system. After preheating the oil is passed through the line 14 to a flash or vaporizing chamber 15, the preheating of the oil being sufficient to drive off the lower boiling point fractions or lighter oils from the hydrocarbon products being treated. This vaporization or distilling off of the lighter fractions may be accompanied by a reduction 85 in pressure produced by means of the regulating valve 16 in the line 14.

The vaporized material is taken off overhead through the line 17 and is passed through a condenser or rectifying stage, not shown, and reduced to a liquid distillate. The unvaporized oil is drawn off through the line 18, controlled by a valve 19 and is picked up by the pump 20 by which it is discharged through the line 21 into the pre- 100

heating coils 9. In the bank of preheating coils its temperature is again raised by being brought in heat exchange relation with the combustion gases passing through the chamber 5. After circulation through the pre-heating coils 9 the oil is directed through a line 22 into the top of the first heating tube 23; the circulation through which will be hereinafter described in more detail. From the tube 23 the oil passes through the line 24 to the tube 25 thence through the line 26 to the tube 27 and finally is discharged through the line 28 into the vaporizing or flash chamber 29. A valve 30 is positioned in the line 28 for reducing the pressure upon the heated oil, if desired.

During the heating of the oil in the tubes a better heat exchange is produced, if sufficient pressure is maintained upon the oil to prevent vaporization insofar as is possible, as it is a well known fact that a better heat exchange can be effected between the combustion gases and a liquid, than with material in vapor form.

On discharge into the vaporizing or flash chamber 29, the lighter fractions are distilled off due to the reduction in pressure, and to the contained heat in the oil, the volatile material passing overhead through the line 31 and the unvaporized material passing down through the line 32 controlled by a valve 33 to the pump 34, where it may be returned through the line 35 to the heat exchanger 13, being discharged through line 36 or diverted from the system through the line 37, controlled by a valve 38. Also, a portion of the oil may be recirculated through the heat exchanger, and a portion diverted from the system according to the desires of the operator.

Referring, now, to the particular design of the heating tubes, and the method used for rotating the liquid column at a high velocity in the respective heating tubes. In describing the details of the tube construction a single tube will be explained, but it is understood that the tubes are identical.

In Figures 4, 5 and 6, at the top of the tube shell 23 is connected by bolted flanges a top assembly 39. The oil discharged from the preheating coil is introduced into the top by means of the pipe 22. The oil passes through the center of the tube in a column or enclosed pipe 40, and is delivered into the rotor of a centrifugal pump 41, mounted upon the shaft 42, which is directly connected with the motor 43, positioned on bottom of the tube. Each of the cylinders 23, 25 and 27 are equipped with a motor of identical construction. The rotor picks up the oil from the vertical column and discharges it at high velocity from the extremity of the rotor vanes, thus imparting to the column of oil in the tube a high rotative speed.

In the top of the tube are spiral vanes 44

which allow the spinning liquid to freely pass and again enter the suction pipe 40 through the duct 46, and also to be partly discharged through the port 45, the latter having connection with the succeeding heating tube or final flash chamber. A liquid is returned through the duct 46 to combine with the oil being introduced. To assure the highest rate of heat transfer through the tube and into the oil column the hot spinning liquid will be rotated at a speed above that required for high turbulence at the point where the liquid meets the heated surface. This will normally be in the order of twenty (20) to thirty (30) feet per second on the heated surface. As the oil is heated its specific weight will decrease relative the oil in the center of the tube—this rise in temperature, and the centrifugal force will bring about radial circulation from the center of the tube to the heated surface.

The main circulation of the oil is downwardly through the central pump suction tube 40, through the pump rotor which imparts rotative movement to the discharged oil. This discharged oil forms a rapidly rotating liquid column surrounding the pump suction tube and having a relatively slow rate of vertical travel. This rate of vertical flow may be varied to meet operating requirements. The entire heating tube is at all times completely filled with oil.

The combustible mixture to be burned in the combustion chambers is as described injected tangentially into the combustion chambers which give a high rotative effect to the total gas volume during combustion, promoting rapid mixing and efficient combustion. Also the passage of the gases of combustion at high velocity over the outer heating surfaces of the tubes improves the rate of heat transfer. The high temperature of the walls of the combustion chambers promote a rapid rate of heat transfer through the heating tubes by radiant heat transmitted radially from the walls to the heating tubes or cylinders. Heat from the gases of combustion in the second and third combustion chambers is transmitted principally by radiation and convection, and by convection through the chamber containing the preheater coil bank. The velocity of the gases of combustion through the combustion and heating chambers is maintained as high as that necessary for the best heat transfer.

It has been found by experimentation with commercial apparatus, comprising a single combustion chamber, tangentially fired surrounding a heating tube, that it is impossible to burn the heating surface or carbonize the oil. It was also found impossible to overheat the walls of the combustion chamber because of the rapid heat absorption of the oil in the tube.

The mechanical energy expended in driving the pump rotor is utilized to impart high velocity of oil over the heating surface maintaining high turbulence and mixing within the liquid column. The operation of the entire heating system comprising preheater coils and three or more centrally arranged heating tubes under pressure without material vaporization, contributes largely to the best rate of heat transfer between heating surface and oil.

The advantages in the system lie primarily in the possibility of maintaining combustion under optimum conditions of low excess air, best fuel economy with the highest attainable flame burst temperatures without danger to the heating surface or combustion chamber walls or oil to be treated. High velocity of gases of combustion through the furnace and a high velocity of oil passing over the heated surface of the tubes offer conditions necessary for the highest rate of heat transfer per unit area.

It will be understood that other methods may be employed for spinning the liquid in the cylinder than the use of a rotor in the lower part of the tube. Satisfactory results have been obtained by tangentially introducing the liquid simultaneously at the upper and lower ends of the cylinder to rotate the liquid. Also, the liquid may be rotated by means of a paddle immersed over a part or full length of the heating tube and driven by an outside motor as is the centrifugal pump or rotor. The construction shown is but a single operable method of rotating the liquid column to produce the desired heat exchange between the circulating liquid and the combustion gases passing through the combustion chambers surrounding the liquid spinning cylinders. Furthermore, in place of the motors 43 any driving means may be used to rotate the oil.

As a substitute for the spinning liquid column the liquid circulation in the heating tubes may be accomplished by effecting a continuous vertical flow through and around a stationary open ended tube positioned coaxially within a hollow heating cylinder, the inlet and discharge being connected to the top or upper part of the cylinder.

I claim as my invention:

1. A cyclic system for heating liquids comprising the steps of introducing the liquid to pass in a straight-line lineal flow to an energy source, converting the lineal flow of the liquid at the energy source to spinning, spiral rotation, subsequently reconverting the spinning energy to lineal flow and recycling a portion of the liquid to the energy source and removing a portion of the liquid while heating the outer surface of the spinning liquid body.

2. A cyclic system for heating liquids comprising the steps of introducing the liq-

uid to pass in a straight-line lineal flow to an energy source, converting the lineal flow of the liquid at the energy source to spinning spiral rotation, subsequently reconverting the spinning energy to lineal flow and recycling a major portion of the liquid to the energy source and removing a minor portion of the liquid while heating the outer surface of the spinning liquid body. 70

3. A cyclic system for heating liquids comprising the steps of continuously introducing the liquid to pass in a straight-line lineal flow to an energy source, converting the lineal flow of the liquid at the energy source to spinning, spiral rotation, subsequently reconverting the spinning energy to lineal flow and recycling a portion of the liquid to the energy source, and continuously removing a portion of the liquid while heating the outer surface of the spinning liquid body. 75

4. A cyclic system for heating liquids comprising the steps of introducing the liquid to pass in a straight-line lineal flow to an energy source, converting the lineal flow of the liquid at the energy source to spinning, spiral rotation to travel in an opposite direction and for substantially the distance of the lineal flow, subsequently reconverting the spinning energy to lineal flow and recycling a portion of the liquid to the energy source, 80 and removing a portion of the liquid while heating the outer surface of the spinning liquid body. 85

5. A cyclic system for heating liquids comprising the steps of passing the liquid in a straight-line lineal flow to a source of energy, converting the lineal flow of the liquid at the source of energy to spinning spiral rotation, said rotation adapted to advance in an opposed direction and for substantially the distance of the lineal flow and in heat exchange relation therewith, reconverting the spinning energy to lineal flow and recycling a portion of the liquid to the source of energy, and removing a portion of the liquid while heating the outside surface of the spinning liquid body. 95

6. A hydraulic machine for heating liquids comprising an outer casing, an inner tube of relatively smaller diameter and means for introducing liquid to the inner tube, a source of energy for converting the lineal flow of the liquid to spinning rotation in the annular space surrounding the inner tube, means for reconverting the spinning energy to straight-line flow and recycling a portion of the liquid to the energy source, and separate means for removing a portion of the liquid continuously. 100

7. A hydraulic machine for heating liquids comprising an outer casing, an inner tube of relatively smaller diameter, means for introducing liquid into the inner tube, a source of energy positioned at the opposite end of the inner tube from the inlet for converting lineal 105

flow of the liquid to spinning rotation in the annular space surrounding the inner tube, means adjacent the inlet for reconverting the spinning energy to straight line flow and for 5 recycling a portion of the liquid to the energy source, and separate means for removing a portion of the liquid continuously.

8. A connected series of cyclic steps for heating liquids, each step comprising the introduction of a feed liquid to pass in straight-line lineal flow to an energy source and there being converted to spinning spiral rotation, reconverting the spinning energy to lineal flow while recycling a portion of the liquid to 15 the energy source and removing a portion of the liquid to be circulated through the subsequent steps, and heating the outer surfaces of the spinning liquid bodies.

9. A cyclic system for heating liquids comprising the steps of introducing the liquid to 20 pass in a straight-line lineal flow to an energy source, converting the lineal flow of the liquid at the energy source to spinning spiral rotation, conserving a portion of the unspent energy of the spinning liquid by recirculation, adding the conserved energy to the lineal flow portion of the cyclic stream, and removing a portion of the liquid while heating the outer surface of the liquid body.

10. A cyclic system for heating liquids comprising the steps of introducing the liquid to 25 pass in a straight-line lineal flow to an energy source, converting the lineal flow of the liquid at the energy source to spinning spiral rotation, conserving a portion of the unspent energy of the spinning liquid by recirculation of a major portion thereof and adding the conserved energy to the lineal flow portion of the cyclic stream, and removing a minor 35 portion of the liquid while heating the outer surface of the spinning liquid body.

CHARLES WALCOTT STRATFORD.
